UNITED STATES PATENT OFFICE

115,591

DESIGN FOR A COAT

Charles Shapiro, New York, N. Y.

Application May 25, 1939, Serial No. 85,195

Term of patent 3½ years

To all whom it may concern:

Be it known that I, Charles Shapiro, a citizen of the United States, residing in New York, New York, have invented a new, original, and ornamental Design for a Coat of which the following is a specification, reference being had to the accompanying drawing, forming a part thereof.

Fig. 1 is an elevation of the back of the coat showing my new design.

Fig. 2 is an elevation of the front thereof.

Fig. 3 is an enlarged section taken on line 3—3 of Fig. 2 showing the structure.

Fig. 4 is a similar sectional view taken on line 4—4 of Fig. 2.

I claim:

The ornamental design for a coat, as shown.

CHARLES SHAPIRO.
